ATTY.

UNITED STATES PATENT OFFICE.

JOHN J. RHINE, OF PITTSBURGH, PENNSYLVANIA.

SHOCK-ABSORBER.

1,303,725.

Specification of Letters Patent. Patented May 13, 1919.

Application filed September 11, 1917, Serial No. 190,865. Renewed April 5, 1919. Serial No. 287,926.

To all whom it may concern:

Be it known that I, JOHN J. RHINE, a citizen of the United States, residing at Pittsburgh, in the county of Allegheny and 5 State of Pennsylvania, have invented new and useful Improvements in Shock-Absorbers, of which the following is a specification.

This invention relates to a shock absorber so constructed as to be capable of supporting a pneumatic reciprocating tool and absorb the shock and vibration created by tools 10 of this character.

An object of the invention is to simplify the construction of a device of this character 15 without sacrificing the efficiency thereof and the durability of the parts.

Besides the above my invention is distinguished in the novel manner of supporting the sleeve on the pipe and allowing adjustment 20 of the tension of the springs.

With these and other objects in view the invention will be better understood from the following detailed description taken in connection with the accompanying drawing 25 wherein:—

Figure 1 is a side elevation of a tool showing my invention applied thereto.

Fig. 2 is a longitudinal sectional view.

Figs. 3 and 4 are cross sectional views. 30 Fig. 5 is a diagrammatic view showing one form of pneumatic tool in operation.

Again referring to the drawing the letter A designates any suitable form of pneumatic tool, and the letter B, the air or fluid 35 conduit. A pipe 1; one element of my invention directly connects the conduit to the tool A, thus accomplishing rigid connection between the tool and conduit. At an intermediate point this pipe has formed thereto 40 in any suitable manner a collar or abutment 2 that is slidably received within a sleeve 3. This sleeve is of a cylindrical outline with both ends threaded as shown at 4 and 5, to receive the interior threads of 45 caps 6 and 7. These caps are identical in construction with the exception that the cap 7 is provided with an extension 8 through which passes a screw 9, the flattened end of 50 which lies upon the flattened space 10 comprising a part of the exterior surface of the

pipe. From this arrangement it will be seen that the tube is free to slide longitudinal of the pipe but held against rotation upon the pipe. Arranged within the sleeve and engaging the abutment on the tube, are 55 springs 11, which also press against the caps 6 and 7. Upon adjustment of the caps upon the sleeve, the tension of the springs can be regulated. For the purpose of preventing subsequent movements of the caps after the 60 adjustment each cap has threaded therein a screw 12 that binds against the adjacent end of the sleeve.

If found advantageous in practice the sleeve may be provided with ears 13, to 65 which may be pivotally connected a handle or support 14, as illustrated in the drawing, the function of which is clearly illustrated in Fig. 5, thus relieving the operator of the tool of a certain amount of stress when the 70 tool is used in mines or similar work where the tool is used in a particular position for a predetermined interval of time.

In the use of the invention the sleeve 3 is gripped by the operator thereby upon each 75 reciprocation of the mechanism of the tool "A" the abutment 2 will move back and forth with the vibrations of the casings of the tool "A". This vibratory motion is resiliently absorbed by the suitably placed 80 springs 11. As the pipe 1 is rigidly connected to the casing of the tool the pipe 1 will vibrate with the tool and by my improved device these vibrations are materially absorbed before they reach the hands of the 85 operator holding the sleeve 3.

It is to be understood that the structural embodiment of the invention as a whole and its various features as shown is merely illustrative and not restrictive, since I am well 90 aware that many of the details of construction can be widely varied without departing from the spirit of the invention. I therefore do not desire to be limited in these particulars or in any other, except as set forth 95 in the appended claim.

Having described my invention what I claim is:

A shock absorber for a reciprocating pneumatic tool comprising an air conveying 100

pipe connected directly to the tool and having an abutment formed thereon, a sleeve in which said abutment and major portion of said pipe is slidably mounted, springs encircling the pipe and engaging the abutment, caps threaded on the ends of the sleeve and engaging the spring for regulating the

tension thereof and to slidably support said pipe and screws mounted in the caps and adapted to engage the sleeve for holding the caps in an adjusted position.

In testimony whereof I affix my signature.

JOHN J. RHINE.
